(57) **CLAIM**

The ornamental design for a rotating brush for washing with water, as shown and described.

DESCRIPTION

FIG. 1 is a top, front and side perspective view of a first embodiment of a rotating brush for washing with water, showing my new design;

FIG. 2 is a top plan view thereof;

FIG. 3 is a side elevational view thereof, the side opposite that shown in FIG. 3 being the mirror image thereof; and, FIG. 4 is a front elevational view thereof.
